UNITED STATES PATENT OFFICE.

PETER BURD JAGGER, OF LONDON, ENGLAND, ASSIGNOR TO QUEBEC SAVINGS AND TRUST COMPANY, OF MONTREAL, CANADA.

COLLAPSIBLE CORE FOR MAKING HOLLOW CONCRETE POSTS AND THE LIKE.

1,172,600.

Specification of Letters Patent. Patented Feb. 22, 1916.

Application filed March 4, 1911. Serial No. 612,394.

To all whom it may concern:

Be it known that I, PETER BURD JAGGER, a subject of His Majesty the King of England, residing at Carlton Studios, Carlton Vale, Maida Vale, London, England, have invented certain new and useful Improvements in Collapsible Cores for Making Hollow Concrete Posts and the like, of which the following is a specification.

10 This invention which is intended for use in molding or casting articles of concrete or the like, relates to collapsible cores of the kind wherein multiple rigid sections are employed in contradistinction to cores comprising a section or sections which in the 15 distention and contraction of the core must be more or less distorted, or in other words leave the article with a wrapping up action.

The object of the present invention is to 20 provide a core of the kind referred to in which there is secured the combined features of presentation by the sections of a configuring surface that is exteriorly entirely complete and a contraction and expansion of the 25 sections that is positive and direct.

A feature of the invention is an arrangement whereby outer sections are distended or contracted with a slower movement than inner sections, such a differential movement 30 enabling exceptionally good joints to be obtained, and rendering the invention specially applicable to cores for manufacturing such long tapering hollow articles as concrete 35 telegraph poles forty feet long or thereabout. Such a core I will proceed to describe with reference to the accompanying drawings, wherein—

The views Figures 1 and 1^a on Sheets 1 and 2 represent if placed end to end in the 40 order given, a complete core in sectional elevation (the section being taken on the line I—I of Fig. 2, Sheet 3) suitable for a long tapering post such as could be utilized as a telegraph pole. Figs. 2 and 3, Sheet 3, are 45 transverse sections of the core on the line II—II Fig. 1^a and III—III Fig. 1 respectively. Fig. 4, Sheet 4, illustrates a modified core under the invention wherein the longitudinal sections may be individually 50 adjusted.

According to the invention, the core is composed of a number of parallel or converging longitudinal sections *a*, *b*, *c*, *d* hav-

ing a shape in cross section corresponding to the inside cross-sectional shape chosen 55 for the article to be made. For instance if the cross sectional interior outline of the article is to be substantially a square, each longitudinal section will be of section as in the example illustrated and the number of 60 the individual longitudinal sections will preferably be four.

The sections are so disposed with relation to each other that conjointly they form a hollow core, with the adjacent edges of individual sections overlapping. This overlapping of the sections is so arranged that the oppositely disposed sections *a*, *c*, and *b*, *d* may be drawn closer together or moved apart, to respectively contract or expand 70 the core.

The sections so disposed are rigidly supported from a rod *e* which runs through the core and may advantageously be disposed centrally thereto. The supporting means 75 in the example illustrated on Sheets 1, 2 and 3 take the form of a series of sets of arms or spiders *f* Fig. 2, or their equivalent *g*, Fig. 3, spaced apart and fixed to the said central rod *e*, and slidably connected to 80 slide-rods or slide-bars *h* running longitudinal of, and carried by, the sections. The slide-rods or slide-bars are set at an angle to the central rod. For instance, in the case of the tapering core illustrated in Sheets 1 85 and 2 they may run parallel or substantially so with the longitudinal sections. Thus by a simple lengthwise movement of the central rod *e* relatively to the core-sections, and in a direction toward the wider end of the 90 core, the sections will be drawn closer together simultaneously over the whole of their length while with a reverse lengthwise movement of the central rod the sections will be similarly moved apart. Such length- 95 wise movement of the central rod may advantageously be effected from the ends of the core by screw-threading an end of the rod *e* and providing a screw nut *o* to turn thereon while working against a fixed abutment such as the end of the core, or, as shown, cross pieces *p* bearing projecting sides of the mold box *q*.

To give the differential movement to the oppositely disposed sections, the slide-rods 105 or slide-bars of those sections which lap in-

side the other sections, will be given a greater angle of inclination to the central rod than the outside lap sections, so that the former will move together faster than the latter when contracting the core, while when expanding the core, the inside lap sections will be caused to press against the outside lap sections and produce a good joint. The edges of the outside lap sections will advantageously be beveled as indicated at *m* correspondingly to their line of movement. A convenient way of arranging this difference in the angle of inclination of the slide-bars to the central rod is illustrated, and consists in securing the slide-bars of the sections *b*, *d* at a distance from the corners of the sections *b*, *d* while the slide-bars of the sections, *a*, *c* are secured directly to the corners thereof. For a distance along the narrow portion of a tapering core, such as is illustrated, distance pieces *n* are, as shown, employed, but as the distance between the slide bars and the corners of the sections increases, corner brackets such as *i* can be substituted.

For long lengths of posts, such as are suitable for telegraph poles, and as in the example of core depicted the longitudinal sections will advantageously each be composed of a number of separate lengths butt jointed and connected by butt straps *j*. Where the slide bars are connected directly to the corners as in the case of the sections *a*, *c*, the slide bars are formed with notches *k* to fit snugly over the straps *j*. The butt straps *j* on the sections *b*, *d* which lap outside the other sections, have their limbs shorter than those of the corresponding sections as shown, in order to leave the requisite clearance for the contraction of the sections.

The central rod *e* may likewise advantageously be made up of separate lengths, a convenient arrangement for connecting which, consists in having the sets of slide-bar engaging arms or spiders *f*, or their equivalent *g* carried by bosses *l* internally provided with right and left handed screw threads, and utilizing these bosses for connecting the central rod lengths which are correspondingly screw-threaded at their ends to engage the bosses, the two ends being pinned in the boss, if desired, to normally prevent possible unscrewing thereof. In practice I have found such pinning unnecessary.

The core can be assembled by threading the slide-bars of the longitudinal sections into the arms *f*, or their equivalent *g*, care being taken to connect the inside lap sections first. Where the longitudinal sections are each composed of a plurality of sections, each part can be threaded separately by arranging a screw connection between one part of the butt straps and the ends of the corresponding sections.

Although for the reason that it constitutes an important application of the invention, I have chosen to describe the embodiment of the invention illustrated in Sheets 1 and 2 with reference to a tapering core for use in manufacturing of an artificial conglomerate, a long tapering hollow post such as could be utilized for a telegraph post, it will be understood that the invention is not limited to tapering hollow posts, but can be utilized for making hollow posts or the like of an artificial conglomerate having the same cross sectional extent throughout.

It will be understood that the invention is not limited to the employment of a single rod common to all the sections. For instance as depicted in Fig. 4 Sheet 4, where the dimension of the article to be made permits, an individual adjustment of each section of the core can be provided for by arranging separate rods *e'*, one for each section. Each rod will carry arms to engage the corresponding slide bar secured to the corresponding section, each rod being supported from a common support such as a frame—and arranged to have a lengthwise movement as hereinbefore described imparted separately thereto. With this arrangement, the inside lap sections would of course be drawn in before the outside lap sections.

By the term posts or the like I include telegraph posts, pipes, hollow floors, hollow partitions, and other such hollow articles, tapering or parallel, made of an artificial conglomerate, and requiring the employment of a collapsible core, and although the invention is particularly applicable for use in making long hollow articles such as telegraph poles of forty feet, more or less, long its range of usefulness will obviously include hollow articles of divers lengths and widths, made in situ or in the factory. Also the cross sectional shape of the core and the numbers of the longitudinal sections which it may comprise can be varied from that chosen for illustration without going beyond the scope of the invention.

For making the articles in the factory, I obtain the best results by consolidating the concrete by means of a machine made and operating according to my previous Patent No. 967,196.

Having now particularly described and ascertained the nature of my said invention and in what manner the same is to be performed, I declare that what I claim is:

A collapsible core comprising a number of rigid sections of which the edges of the alternate sections overlap the adjacent edges of the sections lying intermediate, a rod disposed within the sections, a series of members attached to the rod, slide bars slidingly engaged by said members and secured to the sections out of parallel with the rod, the slide bars actuating the inside sections

being more sharply inclined to the rod than the slide bars actuating the outside sections and means associated with the rod for imparting lengthwise movement to the said member to thereby distend or contract the outer sections with a slower movement than the inner sections.

In testimony whereof I affix my signature in presence of two witnesses.

PETER BURD JAGGER.
